(57) CLAIM

The ornamental design for a bottle, as shown and described.

DESCRIPTION

FIG. 1 is a front view of the bottle;

FIG. 2 is a left side view of the bottle, wherein the right side view is a mirror image thereof;

FIG. 3 is a rear view of the bottle;

FIG. 4 is a top view of the bottle;

FIG. 5 is a bottom of the bottle;

FIG. 6 is a perspective view from above the left rear side of the bottle; and,

FIG. 7 is a perspective view from below the left front side of the bottle.

“77” forms a part of the claimed design and is a trademark of MATSON DE LA POMME FRELIGHSBURG INC.
